UNITED STATES PATENT OFFICE.

JACOB DAVID, OF BROOKLYN, NEW YORK, ASSIGNOR OF ONE-HALF TO
EDWARD A. DEVEAU, OF SAME PLACE.

WANTAGE OR ULLAGE ROD.

SPECIFICATION forming part of Letters Patent No. 280,586, dated July 3, 1883.

Application filed November 16, 1882. (No model.)

To all whom it may concern:

Be it known that I, JACOB DAVID, a citizen of the United States, residing at Brooklyn, in the county of Kings and State of New York, 5 have invented a new and useful Wantage or Ullage Rod, of which the following is a specification.

My invention relates to improvements in rods having a number of scales and figures 10 marked thereon to gage and ascertain the ullage of different-sized barrels which contain liquid. The rods at present in use have a stationary or fixed lip at zero, which lip has to be placed against the under or interior side 15 of the bung-hole stave when inserted into the barrel through the bung-hole.

The object of my invention is to expedite 20 finding the wantage of barrels containing liquid, and to find the wet-line with great accuracy. I attain these objects by substituting a movable lip for the fixed lip at present in use on a wantage-rod, a description whereof is hereinafter more fully set forth, and the mechanism is illustrated in the accompanying 25 drawings, in which—

Figure 1 is a vertical section of the top portion of a wantage-rod with my attachment. Fig. 2 is a cross-section of the rod. Fig. 3 is a cross-section of the rod and attachments on 30 the line *x y*. Fig. 4 is an elevation of the attachment. Fig. 5 is a cross-section of the tube *M* and parts *F C* on the line *x y*.

Similar letters refer to similar parts throughout the several views.

35 *A* is the top portion of a square rod, such as are in common use by gagers, having a number of scales and figures on the several sides to mark the distance from the surface of the fluid in a barrel to the bung-stave and as 40 certain the wantage.

B is a lip that catches under and is held against the under side of the bung-stave when the rod is inserted into a barrel through the bung-hole. The zero-line on the rod is indicated by the dotted line at *B'*. The dotted line marked *B'* also shows where the permanent lip is placed on wantage-rods as at present used.

45 *K* is a cylindrical longitudinal chamber that is made in the rod *A*, as shown by the vertical section, Fig. 1, and the cross-section plan

views, Figs. 2 and 3, and having a slot the whole length of the chamber, from the longitudinal cylindrical chamber *K* to the outside of one side of the rod *A*, as shown at the cross-sectional plan views, Figs. 2 and 3.

55 *H* is a plug that is fitted into the top of the cylindrical chamber *A*, into the under side of which plug is inserted a screw marked *L*.

The tube *M* is just of sufficient diameter to 60 play up and down easily inside the longitudinal cylindrical chamber *K*, and inside the tube *M* is fitted a spiral spring, *G*, which spring *G* is fastened one end to the bottom of the chamber *K* at *P*, and the other end is fastened to 65 the inside of the tube *M* at *Q*. The tube *M* is connected to the handle *C D* and lip *B* by the flat piece *F*, as shown at Figs. 1, 3, 4, and 5, which piece *F* is just the same width as the depth of the slot made from the outside of the 70 rod *A* into the chamber *K*, and not as thick as the width of the slot, as shown at Fig. 3.

To ascertain the distance from the fluid-line to the bung-stave in a barrel containing liquid, insert the rod *A* through the bung-hole and 75 catch the lip *B* under the bung-stave. Hold the lip firmly against and under the side of the bung-hole by the handle *C D*. By pushing down on the rod *A* until the top of the inside tube, *M*, strikes against the set-screw *L* the lip *B* will 80 be at the zero-line, as shown by the dotted line at *B'*, Fig. 1, and the handle *C D*, attached to the lip, will be in the position occupied by the dotted line *C' D'*. Upon releasing the pressure on the rod *A* the spring *G* will draw the 85 rod out of the fluid, when the rod may be removed from the barrel, showing on the rod the distance of the wet-line from the under side of the barrel-stave.

The set-screw *L* can be lengthened or shortened to maintain the lip *B* at the zero-line when the tube *M* is brought in contact with it.

When a lip is fixed and stationary at the zero-line on a wantage-rod, great care must be taken when inserting the rod or the wet-line 95 will show too high on the rod, if the lip is allowed to drop below the under side of the stave; but by having a movable lip on a wantage-rod, which is held in position some distance below the zero-line when inserted into a 100 barrel, no great amount of exactness or care is required, as the true wet-line will not be

found until the rod is pressed down into the fluid and the lip is brought to the zero-line.

What I claim as my invention is—

1. In combination with a wantage-rod, a movable lip held in position by a spring, substantially as shown and described.

2. A wantage-rod having in the top end a longitudinal cylindrical chamber, K, fitted with a plug, H, having a set-screw, L, inserted

therein, in combination with a movable lip 10 having a handle, C D, a sliding tube, M, spring G, and connecting-piece F, substantially as shown and described.

JACOB DAVID.
